UNITED STATES PATENT OFFICE.

MINNA WENSCH, OF BROOKLYN, NEW YORK.

DESIGN FOR A BANDAGE.

SPECIFICATION forming part of Design No. 35,708, dated February 11, 1902.

Application filed August 17, 1901. Serial No. 72,453. Term of patent 7 years.

To all whom it may concern:

Be it known that I, MINNA WENSCH, a citizen of the United States, and a resident of New York city, (Brooklyn,) county of Kings, and State of New York, have invented and produced a new and original Design for a Bandage, of which the following is a specification.

The essential feature of the design consists of a bandage having a V-shaped strap which increases in width from the center toward its ends. The rear end of the strap is provided with an arched edge and the front end with two laterally-projecting wings, joined at their upper edges by a concave curve.

Referring to the drawings, a designates the belt, having an upper straight edge a' and a lower concave edge a''. From the belt a depends a strap b, which is V shape in cross-section and increases in width from the center toward the ends, the V being less pronounced near the ends. The broadened front end is formed with two laterally-projecting wings b', the upper edges of which are joined by a concave curve, and the ends of the wings are rounded. The broadened rear end b' is arched. The front and rear thus shaped merge into a contracted intermediate portion, which from the ends downward assumes a more and more pronounced V shape in cross-section by virtue of the bandage-strap broadening and flattening toward its ends.

What I claim is—

The design for a bandage, substantially as herein shown and described.

Signed by me at New York city, New York, this 16th day of August, 1901.

MINNA WENSCH.
